UNITED STATES PATENT OFFICE

LOUIS J. HARTLE, OF PITTSBURGH, PENNSYLVANIA

LEER

Application filed December 10, 1926. Serial No. 153,844.

This invention relates to furnaces and more particularly to tunnel type furnaces such, for example, as the leers commonly employed for annealing glass articles.

5 An object of this invention is to provide a leer of such construction and arrangement as to permit the utilization of heat which has hitherto been permitted to escape.

A further object is to provide a leer of the 10 type set forth capable of more efficient operation than is possible with similar devices now in use and known to me.

A still further object is to provide a leer 15 of such construction and arrangement that the temperature of any predetermined sections can be controlled independently of any other section.

A still further object is to provide a device 20 of the type set forth of such arrangement that it can be installed directly on a factory floor without the necessity of any sub-structure, and is thus capable of being dismantled and moved from one location to another at a nominal cost.

25 These and other objects which will be apparent to those skilled in this particular art are accomplished by means of the present invention, one embodiment of which is illustrated in the accompanying drawings, in 30 which Figure 1 is a vertical longitudinal sectional view of a leer constructed in accordance with one form of this invention. Fig. 2 is a view of the structure illustrated in Fig. 1, showing the same half in plan and half in 35 horizontal section on the line 2-2 of Fig. 4. Fig. 3 is a transverse section on the line 3-3 of Fig. 1, taken through the firebox. Fig. 4 is a similar view on the line 4-4 of 40 Fig. 1 and Figs. 5 and 6 are similar views on the lines 5-5 and 6-6, respectively, of Fig. 1.

The particular embodiment of the present invention which has been chosen for the purposes of illustration is shown as applied to a tunnel type leer such as commonly employed in annealing glass articles and includes a firebox or combustion chamber where suitable fuel is burned and from which the 50 products of combustion are lead through

flues arranged both above and below the tunnel for the purpose of heating the latter in their travel toward an associated stack. The present invention contemplates controlling the flow of heating fluid through both the upper and lower flues in such a way as to enable the obtaining of any desired temperature gradient from one end of the tunnel to the other. In the present embodiment of this invention this is accomplished 55 by providing one flue with a plurality of outlet ports spaced at suitable intervals longitudinally thereof and connecting these outlet ports with the associated stack. By this means the amount of heating fluid in this particular flue can be reduced during its flow therethrough in any desired manner, as gradually or as suddenly as desired. In order to provide an additional control of the temperature gradient in the tunnel, and also 60 to increase the efficiency of this type of leer, the present invention provides a mechanism for reclaiming a part or all of the heat remaining in the fluid which has passed 65 through the flues and into the stack, and returning such fluid to a heating flue so that heat which would otherwise be lost is thereby utilized.

The particular embodiment of the present invention which has been chosen for the purposes of illustration includes a firebox or combustion chamber 10 having an opening 11 through which a burner 12 projects a suitable flame, and the interior of the firebox is provided with a baffle 13 which is so positioned 80 as to evenly distribute the heating fluid throughout the chamber. Flues or passages 14 connect the firebox with tunnel heating flues 15 which extend longitudinally 85 along the roof of the tunnel. These heating flues are preferably formed of cast iron sections which include a bottom plate 16 forming the roof of the usual tunnel 17 and provided with a number of vertical ribs 18, integral therewith and running longitudinally 90 of the tunnel in such a manner that when a number of these sections are associated in end to end relation a plurality of heating flues 15 are formed along the top of the tunnel, the tops of which flues are formed by 100

suitable plates 19 secured to the vertical ribs in any desired manner.

The firebox is also connected by downwardly extending flues or passages 20 with auxiliary fireboxes 22 communicating with the bottom heating flues 23 which extend longitudinally beneath the tunnel and which are preferably constructed of cast iron sections similar to the sections over the roof of the tunnel. As shown in Fig. 6 the lower heating flues lead to a common chamber or header 24 which is connected, by vertically extending passages 25 and horizontal passages 26 provided with dampers 27, to the usual stack 28. The flues 14 which connect the firebox with the upper heating flues are adapted to be controlled by suitable dampers 29 and the flues 20 leading from the firebox to the lower auxiliary fireboxes 22 are adapted to be opened and closed by suitable dampers 30.

Outlet ports 31 are positioned at predetermined points longitudinally of the upper heating flues 15 and are connected to the stack by a suitable outlet flue or pipe 32. Each port is opened or closed by a damper 33.

A blower 34, driven by a motor 35 or any other desired device is adapted to withdraw heating gases from the stack through an opening 36 and pipe 37 which is controlled by a damper 38 and return them to heat exchanging relation with the tunnel. A damper 39 is provided in the stack so as to permit the blower to reclaim any part or all of the gases reaching the stack. In the present embodiment of this invention the blower forces the heating fluid withdrawn from the stack into a header or pipe 40 which is connected with different points in the lower heating flues by means of a plurality of downwardly extending pipes 41, each of which communicates with a horizontal flue or header 42 extending across the bottom of the leir. Each header 42 is connected with inlet ports 43 leading to the bottom heating flues 23 and dampers 44 control the opening and closing of such ports.

In operation the burner 12 projects a flame through the associated opening 11 into the firebox or combustion chamber 10 where it strikes the baffle and spreads throughout the entire chamber so as to completely fill the same. Suitable air inlet openings 45, see Fig. 3, are associated with the combustion chamber so as to supply atmospheric air thereto and dampers 46 are associated with these openings. From the combustion chamber the heating gases flow through passages 14 to the upper heating flues 15 and through passages 20 to the auxiliary fireboxes 22 and thence to the lower heating flues 23. By suitable regulation with the various dampers 33 which control the opening and closing of the outlet ports spaced longitudinally along the upper heating flue 15 the heating effect of

the gases flowing therethrough can be accurately and delicately adjusted. The speed of the heating gases flowing through the lower heating flues will be controlled by the position of the dampers 27, positioned in the outlet flues leading from the lower heating flues to the stack. By returning the desired amount of heating fluid from the stack to the lower flue 23 a large amount of heat which would otherwise be lost is reclaimed so that the most efficient heating of the leir is obtained. The amount of heating gases reclaimed may be varied by suitably adjusting the draft damper 39 in the stack and the damper 38 in the flue connecting the stack with the blower 34. The point or points of the lower flue to which the reclaimed heating gases are returned can be determined and varied by adjusting the dampers 44 associated with each inlet 43 leading from the pipe 40 to the lower flues.

It will be apparent that the proper regulation of all dampers will produce the desired temperature gradients in the portions of the tunnel adjacent to the top and bottom heating flues, thus making it possible to obtain a substantially uniform temperature in every transverse section or zone of the tunnel. The character of the temperature curves obtained by plotting the temperatures in the tunnel as ordinates and the distances along the tunnel as abscissas is determined by the character of similarly plotted curves for both the bottom and top flues, and these are controlled by the location and adjustment of the dampers in the ports communicating with these flues. It will be apparent that the resulting temperature gradients may be controlled at will and that the point or zone of maximum drop in temperature may be shifted longitudinally of the tunnel to the place desired. For example, the more reclaimed heat that is permitted to enter through a given port of the bottom flue the quicker will be the rise in temperature at that point and this reclaimed heat can be induced at any of the points at which it is desired to raise the tunnel temperature. Obviously the more heat reclaimed the less fuel it will be necessary to supply to the combustion chamber up to a certain point.

Although I have described what I now believe to be the preferred embodiment of this invention it will be apparent to those skilled in this particular art that various changes, additions, substitutions and omissions can be made therein without departing from the spirit of this invention or the scope of the appended claims.

What I claim as new and desire to secure by Letters Patent is:

1. A leir having in combination a tunnel, flues in close heat-exchanging relation therewith for the passage of heating fluid and

- means for repassing at least a portion of such fluid through at least a part of said flues.
2. A leer having in combination a tunnel, flues in close heat-exchanging relation therewith for the passage of heating fluid and means for returning at least a part of such fluid to said flues after it emerges therefrom.
3. A leer having in combination a tunnel, a flue in close heat-exchanging relation therewith for the passage of heating fluid and means for causing such fluid which has passed through said flue to be returned thereto.
4. A leer having in combination a tunnel, a flue in close heat-exchanging relation therewith for the passage of heating fluid, a stack communicating with said flue and means for diverting heating fluid from said stack and returning it to said flue for the purpose of controlling temperatures therein.
5. A leer having in combination a tunnel, a flue in close heat-exchanging relation therewith for the passage of heating fluid, a stack communicating with said flue, a blower adapted to divert heating fluid from said stack and a pipe for returning such fluid to said flue.
6. A leer having in combination a tunnel, a flue in close heat-exchanging relation therewith for the passage of heating fluid, a stack communicating with said flue, a blower adapted to divert heating fluid from said stack, a pipe for returning such fluid to said flue and connections between said pipe and different points of said flue whereby said fluid can be returned thereto at any of said points.
7. A leer having in combination a tunnel, heating flues in close heat-exchanging relation therewith including a flue beneath the bottom of said tunnel and means for returning at least a part of the heating fluid which has passed through said flue to said bottom flue.
8. A leer having in combination a tunnel, heating flues in close heat-exchanging relation therewith including a flue beneath the floor thereof, means for returning at least a part of the heating fluid passing through said flues to said bottom flue and connections for permitting such fluid to enter said flue at a predetermined point longitudinally thereof.
9. A leer having in combination a tunnel, a flue in close heat-exchanging relation therewith, means for supplying said flue with a heating fluid, a plurality of ports spaced longitudinally of said flue and means for returning heating fluid which has passed through said flue to one or more of said ports.
10. A leer having in combination a tunnel, a plurality of heating flues in close heat-exchanging relation therewith arranged for the conveyance of heating fluid through said flues in the same direction and means for return-
- ing the fluid to said flues after it has emerged therefrom.
11. A leer having in combination a tunnel, heating flues located above and below said tunnel and means for transferring heating fluid from a flue above said tunnel to one below said tunnel.
12. A leer having in combination a tunnel, a plurality of flues in heat-exchanging relation therewith, including flues above and below said tunnel, means for regulating the passage of heating fluid in spaced longitudinal portions of said flues for controlling the temperature in said tunnel, and means for transferring the heating fluid to portions of the lower flue after said fluid has emerged from said upper and lower flues.
- In testimony whereof, I have hereunto subscribed my name this 2nd day of December, 1926.
- LOUIS J. HARTLE.
